(57) **CLAIM**

The ornamental design for an electrophoresis & electrotransfer device, as shown and described.

DESCRIPTION

FIG. 1 is a front perspective view of an electrophoresis & electrotransfer device, according to an embodiment;

FIG. 2 is a front perspective view of FIG. 1 WITH LID ON;

FIG. 3 is a front view of FIG. 1;

FIG. 4 is a back view of FIG. 1;

FIG. 5 is a right side view of FIG. 1;

FIG. 6 is a left side view of FIG. 1;

FIG. 7 is a top view of FIG. 1; and,

FIG. 8 is a bottom view of FIG. 1.

The broken lines in FIG. 8 depict portions of the electrophoresis and electrotransfer device that form no part of the claimed design.
